UNITED STATES PATENT OFFICE.

MARVIN FERREE, OF NEW YORK, N. Y., AND JOSEPH WISSMAR, OF CLEVELAND, OHIO,
ASSIGNORS, BY DIRECT AND MESNE ASSIGNMENTS, TO PICTURE TRANSMISSION
CORPORATION, OF NEW YORK, N. Y., A CORPORATION OF DELAWARE.

METHOD OF TRANSMITTING PICTURES AND SENDING PLATE THEREFOR.

Application filed January 28, 1925. Serial No. 5,258.

This invention relates to a new and improved method of transmitting pictures by means of electrical pulses and for a new and improved sending plate adapted to be used in connection with said method.

One of the objects of this invention is to provide a method of transmitting pictures by means of a series of electric pulses whereby those portions of the picture which correspond to the intermediate or gray portions thereof shall be sufficiently emphasized so that the reproduced picture will properly correspond to the original picture.

Another object of this invention is to devise a method of transmitting pictures by means of a series of electric pulses whereby the electric pulses, or the intervals between electric pulses will be extremely long when the gray or intermediate portions of the picture are being transmitted.

Another object of this invention is to devise a new and improved broken tone transmitting plate of the picture to be transmitted in which the picture consists of a series of separated and parallel lines of varying thickness, and in which said plate will be free from these parallel lines in those portions of said plate corresponding to the intermediate or gray portions of the picture to be reproduced.

Other objects of this invention will be set forth in the following description and drawings, it being understood that the above general statement of the objects of this invention is intended, not to limit the invention, but to generally explain the purposes thereof.

Fig. 1 shows a transmitting plate of a picture to be reproduced, made according to the old method.

Fig. 2 shows a plate made according to this new and improved method and to be used in transmitting pictures according to the new and improved method.

It has been previously suggested to use a broken tone plate of the picture to be transmitted, in order to transmit the said picture by means of a series of electric pulses and this, for example is shown in U. S. Patent No. 577,373, issued on Feb. 16, 1897, to Noah S. Amstutz, and in U. S. Patent No. 1,026,297, issued on May 14, 1912, to Thomas Thorne Baker. In the methods previously used, the half tone plates em-

ployed for controlling the series of electric pulses were made as shown in Fig. 1 and by the ordinary method employed in making half tones so that the entire picture was broken up into separated areas save where the natural composition or color effect of the picture to be transmitted caused the transmitting plate to have solid white or black areas. If, however, the composition of the picture to be transmitted was such that it was composed throughout of intermediate or gray tones of varying intensity, then the entire transmitting plate was broken up as illustrated in Fig. 1.

According to this invention, the transmitting plate, which is preferably a negative, is produced by being exposed in such manner that the lighter tones of the picture and particularly the background thereof, are accentuated so that corresponding solid dark masses are produced in the same negative, as illustrated in Fig. 2.

The picture to be reproduced is first placed in front of an ordinary camera so that a negative can be made thereof. This negative is made upon an ordinary transparent glass plate, either wet or dry. Before the negative impression is made, a transparent grating having a series of parallel opaque lines is placed in the camera before the negative, so that the negative image consists of a series of parallel opaque lines of varying width, and the continuous tone of the picture to be transmitted is thus duplicated in what may be called broken tone.

The spacing of the opaque lines may vary, and without being limited to any particular spacing, it has been found that a grating having sixty-five (65) lines to the inch is satisfactory for reproducing ordinary photographs. The width of the said opaque lines may be equal to the distances between them, although various types of grating may be employed. By using gratings having parallel lines, a superior effect is produced for this particular purpose, in contrast with gratings having lines crossing each other, because by using a single grating having parallel lines, the points of light in the picture to be transmitted are spread out only in the vertical direction instead of being spread out both in the vertical and in the horizontal direction. It is preferred to have the opaque lines of the grating held horizontally

when the negative is taken. The negative thus produced is now used for making an enlarged positive by means of an ordinary camera and it is preferred that this positive should be twice as large as the negative of the original picture. The enlarged positive thus produced is now printed upon a thin plate made of copper or other suitable bendable metal by means of an ordinary printing frame. This metal plate, which may be called the transmitting plate, has a sensitive coating comprising fish glue, ammonium bichromate and white of eggs. This coating can be made of 16 ounces of fish glue, 1 ounce of ammonium bichromate, 6 egg whites and either 17 or 34 ounces of water. These ingredients are thoroughly mixed and they are spread upon the highly polished surface of the copper plate. The coating is then dried, in which condition it is not very sensitive to daylight but it is sufficiently sensitive to the powerful arc light used for printing thereon from the enlarged positive so that a negative can be printed upon the transmitting plate.

It has been customary heretofore to expose the copper plate to the said arc light for a period of about forty-five (45) seconds to produce the type of plate shown in Fig. 1. According to this invention, the exposure is continued for about seventy-five (75) seconds so as to produce the type of plate found in Fig. 2, which corresponds exactly to the plate shown in Fig. 1, except for the difference in the time of exposure.

This printing is carried out for a sufficiently long period to enable the light gray background of the picture to appear as a solid black background in Fig. 2 and to also cause the light gray tones corresponding to the composition of the picture to appear as solid black or continuous areas in the improved negative found in Fig. 2.

After the copper plate has been exposed, it is washed in cold water until the portions of the coating which have not been acted upon by the light are washed away and the plate is then dipped in aniline dye which is absorbed by the remaining glue or gelatine so as to furnish a reproduction of the image, in order to determine whether or not the photographic work has been properly done. The plate is then washed to remove any surplus dye and it is then baked over suitable flame or the like until the adherent coating has been formed into a hard enamel-like insulating material. After the enamel has been formed, the plate is cleaned by rubbing it with a mixture of ordinary salt (NaCl) and dilute acetic acid, as the action of the acid and of the salt (which is an abrasive) removes any part of the gelatine which does not correspond to the image so as to produce clean bright copper lines between parallel lines of enamel of varying width

without etching the plate. This plate is now bent so that it can be placed upon the transmitting drum heretofore used for the transmission of the picture and illustrated in the previously mentioned Amstutz and Baker patents, so that the lines of copper are parallel to the axis of the drum.

The receiving mechanism may be of the electrolytic type shown in this Baker U. S. Patent No. 1,026,297 so that a negative of the picture to be transmitted is produced at the receiving station. The markings produced at the receiving station may be caused to spread out by making the point of the reproducing stylus of sufficient thickness so that a continuous tone reproduction is secured at the receiving station, free from any of the line effects shown in Fig. 1 or in Fig. 2.

Practical experience has shown that in the system of transmission above mentioned that the reproduced picture does not show any sufficient distinction between the various grayish tones found in the original picture so that a uniform flat effect is produced, which is undesirable because the outline of the picture is not distinct and cannot be clearly distinguished from the background and because the body of the picture does not show any sufficient distinction or sharp gradation between the areas or portions of varying grayish tone.

Experience has shown, however, that by exposing the picture for a sufficiently long time so as to secure a plate corresponding to a picture in which the light gray tones are replaced by solid white areas, that the reproduced picture is clear in outline and in detail.

While the picture to be reproduced may be retouched in the ordinary manner now employed for making half tone reproductions, the over-exposure before mentioned obviates the necessity for retouching the background and in addition it automatically differentiates the light gray tones of the picture from the darker gray tones thereof, which could not be effectively done by an artist.

The period of the additional or over-exposure may vary somewhat depending upon the character of the picture to be reproduced so that it is not intended to limit the invention to the specific example previously mentioned.

The over-exposure before mentioned is particularly important when the broken tone plate consists of a series of parallel and separated lines of varying width because a plate of this character omits so much of the detail in the original picture that unless the lighter tones of the said picture are accentuated by over-exposure, the reproduced picture does not have a great deal of the detail found in the original. For this

reason it has been proposed heretofore to use ordinary half tone transmitting plates, in which the plate consisted of a series of separated dots of varying size, but the use 5 of plates of this character for transmission purposes has been accompanied with such difficulties that it has been proposed to use a transmitting plate composed of a series of separated and parallel lines of varying 10 width.

According to this invention, it is possible to use a transmitting broken tone plate consisting of said parallel and separated lines of varying width and to produce a satisfactory reproduction of the original picture. 15

A preferred embodiment of this invention has been disclosed, but it is clear that numer-

ous changes and omissions could be made without departing from its spirit.

We claim:

A method of transmitting a picture which consists in producing a series of electric pulses corresponding to the differences in light value of the successive small areas of said picture, and producing electric pulses 20 of the type which substantially correspond to a pure white tone in transmitting the small areas which correspond to light grey tone.

In testimony whereof we hereunto affix 25 our signatures.

MARVIN FERREE.
JOSEPH WISSMAR.
